UNITED STATES PATENT OFFICE.

GEORGE R. PAIGE, OF CANTON, MASSACHUSETTS.

CARDING-MACHINE CONDENSER.

Application filed June 28, 1923. Serial No. 648,202.

To all whom it may concern:

Be it known that I, GEORGE R. PAIGE, a citizen of the United States, residing at Canton, in the county of Norfolk and State of Massachusetts, have invented new and useful Improvements in Carding-Machine Condensers, of which the following is a specification.

The object of this invention is to prevent interference between ropings passing from the ring doffer to the roping spools of a carding-machine condenser, the condensed ropings being wound on said spools, which are mounted in the usual winding frame at one end of the machine and driven as usual.

The roping stretches passing from the ring doffer to the winding rolls are in close proximity to each other. The surface of each roping usually carries laterally projecting fibers, not incorporated in the condensed body of the roping and having free outer ends. The said stretches are so close together that fibers projecting from one stretch are liable to interfere or be entangled with fibers projecting from the adjacent stretch or stretches, this interference being a serious objection, because it renders necessary constant inspection of the stretches on their way to the spools, and the separation of entangled fibers between adjacent stretches. If this separation is not effected before the ropings are wound on the spools, the interference causes imperfections in the interfering ropings, when they are subsequently separated.

I attain the object of the invention by providing shearing rolls, as hereinafter described, adapted to trim projecting fibers from opposite sides of the roping stretches before they reach the winding spools, so that fibers on any stretch are prevented from interfering with fibers on the adjacent stretch or stretches.

Of the accompanying drawings forming a part of this specification,—

Figure 1 is a fragmentary elevation, showing somewhat conventionally the ring doffer, the feed aprons, and two of the roping spools of a well known type of carding machine condenser, and shearing rolls adapted to act on the roping stretches passing between the ring doffer and the winding rolls.

Figure 2 is a fragmentary elevation looking from the opposite side, and showing in section the parts represented by Figure 1,

the gears which actuate the shearing rolls being omitted.

Figure 3 is a fragmentary view, showing in side elevation portions of the shearing rolls and the gears connecting the same.

Figure 4 is a section on line 4—4 of Figure 3.

Figures 5 and 6 are magnified cross sectional views of two adjacent roping stretches, Figure 5 showing said stretches before, and Figure 6 after, the trimming operation.

The same reference characters indicate the same parts in all of the figures.

Figures 1 and 2 show the ring doffer 12, two of the winding spools 13, and two pairs of rubbing aprons 24, interposed between the ring doffer and the rolls, these elements being so well known in carding-machine condensers that further description thereof, and a disclosure of the means for operating the same are not necessary.

In carrying out my invention I interpose at any suitable point between the ring doffer and the winding spools a pair of shearing rolls, one above the other, and fixed to shafts 14, 14, which are journaled in fixed bearings (not shown) on the usual frame of the machine. Each roll includes a cylindrical body portion 15 and a plurality of spaced apart annular shearing knives 16. Said knives may be integral with the body portions 15, and formed by peripherally grooving a cylindrical metal body, to form the knives and annular grooves or spaces 17 therebetween. The knives of each roll enter the annular spaces 17 between the knives of the other roll. The intersection of the periphery and the sides of each knife form two annular shearing edges on each knife, the edges of the knives on one roll being in shearing contact with those of the knives on the other roll.

The shearing rolls are arranged so that stretches 18 of ropings on the way from the ring doffer to the spools 13, pass between the rolls, as shown by Figures 3 and 4.

Loose fibers projecting from the surfaces of the stretches 18, as shown conventionally by Figure 5, are trimmed from opposite sides of the stretches, as indicated by Figure 6, so that interference between adjacent stretches is prevented.

I prefer to locate the shearing rolls between the two pairs of aprons 24, as shown by Figures 1 and 2, said aprons being spaced

apart to permit the interposition of the shearing rolls between one pair and the other. The shearing rolls are driven simultaneously in opposite directions, by any 5 suitable means, including, in this instance, a gear 20 (Figure 1) fixed to the shaft which drives one of the aprons 24, a gear 21 fixed to the shaft of the lower shearing roll and meshing with the gear 20, and a 10 gear 22 fixed to the shaft of the upper shearing roll and meshing with the gear 21. The gear 20 may be driven by a larger gear 23, which is driven in any suitable way by the power of the machine.

15 I claim:

In a carding-machine condenser which in-

cludes a ring doffer, roping spools spaced therefrom, to wind ropings coming from the ring doffer; means for trimming opposite sides of the said ropings, said means comprising a pair of shearing rolls arranged in the path of the ropings between the ring doffer and the roping spools, and means for rotating said rolls simultaneously in opposite directions, each roll including spaced 20 25 apart annular shearing knives entering annular spaces between the knives of the other roll.

In testimony whereof I have affixed my signature.

GEORGE R. PAIGE.
